UNITED STATES PATENT OFFICE.

WILLIAM P. BETTENDORF, OF BETTENDORF, IOWA; J. W. BETTENDORF ADMINISTRATOR OF SAID WILLIAM P. BETTENDORF, DECEASED.

HYDRAULIC PRESS.

1,028,986.

Specification of Letters Patent. Patented June 11, 1912.

Application filed January 14, 1910. Serial No. 538,038.

To all whom it may concern:

Be it known that I, WILLIAM P. BETTENDORF, a citizen of the United States, residing at Bettendorf, in the county of Scott and 5 State of Iowa, have invented new and useful Improvements in Hydraulic Presses, of which the following is a full, clear, and exact description.

My invention relates to hydraulic presses 10 and their connections and is adapted to be used in connection with the pipes connecting what is commonly known as the "pull-back cylinders" of such a press and the accumulator coöperating therewith.

15 The principal object of my invention is to prevent, by automatic means the possible danger to life and limb of the operators, or injury to the valuable dies and mechanism of hydraulic presses when a break occurs 20 in the pipes connecting the pull-back cylinder or cylinders thereof to the counter-balancing accumulator.

A further object of my invention is to provide means that will permit the flow of 25 the water through it in either direction, but which will automatically close, and lock the ram and its load in whatever position it may be in, at the time the break in the pipe-line occurs.

30 A further object of my invention is to permit the escape of a jet of water should the operator, unaware of the break in the pipe-line, attempt to operate the press, and if desired utilize said jet to warn the operators, and enable them to avoid a greater catastrophe. This I accomplish by the 35 means hereinafter fully described and as particularly pointed out in the claims.

In the drawings:—Figure 1 is a top plan 40 view of the emergency valve of my invention. Fig. 2 is a side elevation of the same. Fig. 3 is a similar view of the opposite side of said valve. Fig. 4 is a vertical central section of the same. Fig. 5 is a bottom plan 45 view thereof. Fig. 6 is a diagrammatical view of the system including the several mechanisms embodying my invention.

In the drawings 2 represents a hydraulic press including its bed, its platen, its ram, 50 and its bolster, with the cylinder for the ram made integral therewith, and 3, 3, represent the "pull-back" cylinders, which are

made integral with the bolster, and are located on each side of the ram. The pistons, 4, of these pull-back cylinders have the 55 platen of the press attached to their lower ends and their duty is to lift the platen, the heavy dies carried thereby, and the ram after the dies have performed their work, back to their original positions. These pull-back cylinders are connected by branch pipes 5, 5, to a pipe 6 that leads to and communicates with the lower end of an "accumulator," 8, which latter comprises a vertically disposed cylinder having a piston-head therein, the piston of which extends out of the upper end of its cylinder and is weighted in any suitable manner. When the water is forced out of the pull-back cylinder by the downward movement of the 70 ram, it flows through pipes 5 and 6 into the accumulator cylinder and lifts the piston-head and piston thereof, and a total weight slightly exceeding the combined weight of the platen, the dies, the ram and the pull-back pistons, and after each working movement of the ram; this weight, through the medium of the water, automatically restores the platen, and ram, and dies to their original positions. At the junction or 75 confluence of the pipes 5, 5, with pipe 6, which latter is, preferably, located right next the bolster of the press, I arrange automatic devices, which in the emergency of a leak of sufficient magnitude occurring anywhere 80 in pipe 6, will close and confine the water in the pull-back cylinders, and lock the ram, the platen, the dies and so forth in the position they may be in at the time of the break. This automatic device consists of a floating- 85 valve, and escape-vent combined in the same casing or housing. In the drawings, A, represents the metal housing for said valve and bears a crude resemblance in shape to the letter "d" when viewed in the position shown 90 in Fig. 4. The inlet a, to which pipe 6 is connected, is located at the lower angle of the loop of the "d" of the housing, and the bore b leading from said inlet extends upward and then laterally to the vertical body of the 95 housing, and then continues vertically to the upper wider chamber B in the upper portion of the vertical part thereof, thus pursuing a stepped course therethrough, substantially 100

as shown. The upper end of chamber B is closed by a circular or other suitably shaped head C, which is held in place by screws, and has its inner surface constructed so as to 5 compress a suitable gasket or ring in the rabbeted edge of the upper end of chamber B. This head C is also provided with a central boss d, which extends down into and is concentric with chamber B, and is provided 10 with a vertical central bore or dash-pot C', the upper part of which has escape vents, and the mouth of which is slightly contracted to form a guide-bearing for the upper end of the vertical central stud or 15 spindle e of the valve D. This valve consists of a circular disk the margins of the underside of which are seated on the shoulder, E, made by increasing the diameter of the main-passage to form chamber B, and 20 said valve is opened against the expansive pressure of a coil-spring interposed between it and said head C.

The underside of valve D is, preferably, 25 provided with integral depending wings, that radiate from the axial sides of the bore b to guide the valve and prevent its tipping or binding.

Chamber B, has usually two outlets, F, leading laterally therefrom through pipes, 30 5, to the "pull-back" cylinders of the press, and has an escape vent g, extending from it, preferably at right angles to the axes of said outlets, in the outer wider portion of which a spindle-valve G, has reciprocal play. Near 35 the seat for the beveled inner end of this spindle-valve, said vent is provided with an offset passage h, and when the pressure against the inner end of valve G is enough to move it outward a distance sufficient to 40 uncover the entrance to said passage, the liquid or water under pressure will escape through this vent into the outer atmosphere in the vicinity of the operator, and prevent the explosion which might otherwise occur 45 if the operator should attempt to operate the press after a break in the pipe-line, and warn him to cease the attempt, as will hereinafter more fully appear. The outer end of valve G, is, preferably, reduced and seated 50 in the central socket of a centering-plate j for a comparatively heavy coil-spring I, which latter alines with valve G, and has its outer end seated in a centering-plate J corresponding to j. This outer centering-plate 55 has a gage-screw K engaging the outer side thereof, which screw is tapped through the bend of a suitable yoke k, and is manipulated to obtain a resistance for said valve G, exceeding that to which its inner end 60 would be subjected when the water in said pipe-line was under its normal operative pressure.

The lower portion of the vertical part of the D-shaped housing A is provided with 65 a vertical cylindrical chamber, L, which ex-

tends upward from the lower end of the housing to a horizontal plane just below the lateral portion of the main-passage b. The lower end of this cylindrical chamber is closed by a suitable circular-head M, similar 70 in construction to head C, and near its lower end said chamber, L, is connected, by a lateral passage m, that extends through the lower stretch of the loop of the housing, with the main-passage b near its entrance. 75 At its upper end this chamber, L, is provided with a vent, r, that is always open for the escape of any seepage that may accumulate therein.

Chamber L is, preferably, greater in diameter than the main-passage, and has a piston-head N therein, to which a piston-rod n is secured that extends centrally up through a suitably packed opening in the web of metal separating chamber L from 80 the upper portion of the main-passage, and its upper end engages the underside of valve D.

To understand and appreciate the operation of this improved valve, it must be borne 90 in mind that the pressure of the water throughout the system in which said valve is installed, is, under normal conditions, constant, and that the flow through it is slow and even. When the water under pressure 95 is released from the cylinder of the press, back of the ram, the water will slowly flow through the passage, b, and out of the outlets F of the housing to the "pull-back" cylinders. At the same time the water will 100 also flow through port or passage m into the chamber L under piston-head N, and as the pressure on the underside of said piston-head (which is greater in area than valve D) is greater than the pressure opposing the 105 opening of valve D, said piston n will hold valve D off its seat and keep it off its seat continually, and permit the free passage of water past the same no matter in which way it may be flowing. If, however, the ram and 110 parts connected thereto were at the limit of their upward movement, and a break in the pipe-line 6 should occur, thus releasing the pressure under valve D, the latter would immediately shut down upon its seat and 115 close bore b, by the pressure on its upper side caused by the ram and platen and other parts supported thereby, and the water thus confined, would support the pull-back pistons and the ram, platen, and dies and prevent them dropping or descending. When the ram and its parts were thus locked, should some one, not knowing about the 120 break, attempt to operate the press by admitting water to the cylinder of the ram, the pressure caused by the downward movement of the "pull-back" cylinders would 125 open valve G and the offset passage h and the water would discharge with considerable force, and; if a hose were employed could 130

be directed toward the position usually occupied by the operator, and thus warn him so that he could turn off the pressure back of ram and stop the operation of the press and 5 avoid greater danger.

What I claim as new is:—

1. The combination with a hydraulic press having a pull-back cylinder for the platen thereof, of an accumulator cylinder, pipe 10 connecting the same to said pull-back cylinder, a floating valve that automatically closes said pipe when a break occurs therein between the valve and the accumulator, and a valve-controlled safety-vent between said 15 floating valve seat and the pull-back cylinder.

2. In mechanism of the kind specified, an emergency valve for connecting the pull-back cylinder and accumulator pipes comprising a suitable housing having a stepped passage therethrough, the outlet end of 20 which is enlarged to form a valve chamber, which latter has a lateral outlet, a valve controlled safety vent leading therefrom, a 25 floating valve adapted to close said chamber, and means movable in the direction of the length of said chamber and actuated by the water pressure entering said passage and adapted to hold said valve open.

3. In mechanism of the kind specified, an emergency valve for connecting the pull-back cylinder and accumulator pipes comprising a suitable housing having a stepped passage therethrough, one end of which is 35 enlarged to form a valve-chamber, having a lateral outlet, an automatically returnable valve adapted to close said chamber, a valve-controlled safety vent leading from said chamber, a cylinder, and a piston in the 40 same, which latter moves in the direction of the length of said chamber, is actuated by the pressure of the water entering said passage and is adapted to open said valve.

4. In mechanism of the kind specified, an 45 emergency valve for connecting the pull-back cylinder and accumulator pipes comprising a suitable housing having a stepped passage therethrough, the outlet end of which is enlarged to form a valve-chamber, 50 which latter has a lateral outlet, a safety vent leading from said chamber, a graduated pressure valve controlling said vent, a floating valve adapted to close said chamber, and means movable in the direction of the 55 length of said chamber, and actuated by the

water pressure entering said passage, and adapted to open said valve.

5. In mechanism of the kind specified, an emergency valve for connecting the pull-back cylinder and accumulator pipes comprising a suitable housing having a stepped passage therethrough, one end of which is 60 enlarged to form a valve-chamber having a lateral outlet and a safety vent leading therefrom, a regulated tension floating valve 65 adapted to close said chamber, a graduated pressure valve controlling said vent, a cylinder, and a piston in the same, which latter moves in the direction of the length of said chamber, is actuated by the pressure of the 70 water entering said passage and is adapted to open said valve.

6. In mechanism of the kind specified, an emergency valve for connecting the pull-back cylinder and accumulator pipes comprising a suitable housing having a stepped passage therethrough one end of which is 75 enlarged to form a valve-chamber from which a lateral outlet leads, a floating valve closing said chamber, having an axial spindle, a head closing the opposite end of said chamber having a dash-pot engaged by said valve-spindle, a graduated resistance controlling valve closing said vent, a cylinder, a piston in the same movable in the direction 80 of length of said chamber, which is actuated by the pressure of the water entering said passage, and is adapted to open said valve.

7. In mechanism of the kind specified, an emergency valve for connecting the pull-back cylinder and accumulator pipes comprising a suitable housing having a stepped passage therethrough, the outlet end of 90 which is enlarged to form a valve-chamber, which latter has a safety vent, leading therefrom, a spindle valve controlling said vent, a spring bearing against the outer end thereof, a gage-screw for graduating the pressure thereof against said spindle valve, a floating valve adapted to close said chamber, and 95 means movable in the direction of the length of said chamber and actuated by the water pressure entering said passage and adapted to open said valve.

In witness whereof I have hereunto set 105 my hand this 10th day of January 1910.

WILLIAM P. BETTENDORF.
